ATTORNEY.

UNITED STATES PATENT OFFICE

2,489,010

STOCKING STRETCHER.

Bernard Corwin, East Orange, N. J.

Application, July 14, 1947, Serial No. 760,864

2 Claims. (Cl. 223—77)

1

This invention relates to improvements in devices for drying hose, stockings and the like without shrinkage; the device being particularly useful in drying woolen hose which have a pronounced tendency to shrink upon being washed and dried.

While many devices have been proposed for the aforementioned purpose, it is an object of the present invention to provide a simple, compact hose-drying device having a minimum number of parts which may be easily fabricated and inexpensively assembled to produce a durable and efficient unit.

Another object of the invention is the provision of a hose-drying device of the character indicated which may be easily adjusted to any desired size and which will retain its adjusted position securely and positively while the hose or stocking is pulled over the device and during the drying process.

A further object of the invention is the provision of a hose-drying device free from any catches, projections or the like which might injure hose in the operation of being pulled over the device.

The foregoing objects, as well as additional objects and advantages of the invention will be readily apparent in the course of the following detailed description taken in connection with the accompanying drawing which illustrates a preferred embodiment of the invention, and wherein:

Fig. 1 is a side elevation of a hose-drying device embodying the features of the invention and showing the adjustable foot portion of the device in completely retracted position.

Fig. 2 is a fragmentary sectional view taken along line 2—2 of Fig. 1, and clearly showing the series of spaced corrugations on the slidable foot portion with which the transverse bar of the frame is selectively engageable.

Fig. 3 is a transverse sectional view taken on line 3—3 of Fig. 1, illustrating the slidable engagement of the parallel arms of the frame within the marginal sleeves formed in the foot portion.

Fig. 4 is a transverse sectional view taken on line 4—4 of Fig. 1.

Fig. 5 is a fragmentary side elevation similar to Fig. 1 but showing the adjustable foot portion of the device partially extended, the transverse bar of the frame being engaged in one of the intermediate members of the series of corrugations in the foot portion.

Referring now to the drawing in detail, the

device comprises a frame 10 preferably formed as a unitary structure from a piece of wire in simulation of the contour of the leg and foot, and having a pair of arms or branches 11 interconnected by a transverse bar 12 at the lower end of said frame. In order to impart rigidity to frame 10, one of the arms 11 is preferably turned inwardly at its upper end and secured to the other of said arms by soldering, welding or in any other desired manner, to form the upper connecting arm 13. Frame 10 is also provided with an upper hook 14 for suspending the device conveniently.

An extensible toe-plate 15 is provided adjustably and slidably engageable with the lower portion of frame 10, defined by arms 11 and transverse bar 12. Said toe-plate is preferably formed with an integral, U-shaped, hollow marginal flange extending completely around the side edges and lower rounded edge thereof to define sleeves 16. The inner edge 16a of sleeves 16 is spaced from the body of the toe-plate 15 for the slidable reception of transverse bar 12 of the frame 10, the arms 11 each being disposed slidably within a respective sleeve 16 of said toe-plate. The extremities of transverse bar 12 are preferably swaged or reduced in thickness adjacent the points where said extremities merge with arms 11, as indicated at 17.

Toe-plate 15 is further provided with a series of spaced corrugations, or depressions 18, for selective engagement with the transverse bar 12 in order to adjust the frame 10 to any desired size of hose or stocking. Said corrugations may be struck from the body of toe-plate 15 by a simple stamping operation.

In order to prevent inadvertent separation of toe-plate 15 from arms 11 and transverse bar 12, the upper end of each sleeve 16 is preferably crimped over, as shown at 19, after frame 10 has been engaged with said toe-plate in the above-described manner.

In the actual operation of drying hose or stockings, the article is pulled over the device after adjusting said device to the proper size and the device is hung or suspended to dry the article. Slidable toe-plate 15 may be simply and easily adjusted toward or away from transverse bar 12 of frame 10, said transverse bar being selectively engageable with that particular member of the series of corrugations or depressions 18 which will fix the toe and foot portion of the device to the proper size to conform to the foot of the hose or stocking to be dried without shrinkage. If desired, the corrugations 18 may

be indexed or calibrated to correspond to the conventional hose and stocking sizes and to aid in quickly adjusting the device.

The device may be constructed from any suitable material which will not have a deleterious effect on fabrics such as galvanized iron, metal having a rustproof coating, synthetic plastic and the like. The device is eminently simple, efficient in operation and rugged comprising but two parts, the frame 13 and adjustable toe-plate 15, both of which may be fabricated inexpensively in a minimum number of stamping and bending operations.

It will be noted that by forming sleeves 16 as an integral, U-shaped, hollow flange extending completely around the sides and rounded edge of toe-plate 15, the retraction of said toe-plate with respect to transverse bar 12 is automatically limited, as clearly shown in Fig. 1, to the point where the width of said toe-plate between the inner surfaces of said sleeves becomes less than the overall length of transverse bar 12. Thus, the need for separate limiting or stop means is eliminated and the design of the device is simplified.

Since certain modifications may be made in the device of the invention without departing from the scope thereof, it is intended that all matter contained in the foregoing specification and shown in the accompanying drawing be interpreted merely as illustrative and not in a limiting sense.

Having thus described my invention, what I claim as new and desire to secure by Letters Patent is:

1. A device of the character described for shaping and drying hose, stockings and the like, said

device comprising a unitary frame having a pair of spaced arms defining a leg portion and a lower transverse bar interconnecting said arms, and a toe-plate extensibly and adjustably engageable with said frame, said toe-plate having a linear upper edge, a pair of side edges and a rounded lower edge continuous with said side edges, said toe-plate having an integral marginal flange coextensive with said side edges and said rounded edge to define a pair of sleeves for the reception of the arms of said frame, the inner edge of said sleeves being spaced apart from the body of said toe-plate, the extremities of said transverse bar being reduced in thickness adjacent each arm of said frame, said reduced extremities of said transverse bar being slidable between said inner edge of said sleeves and the body of the toe-plate, said toe-plate having a series of transverse corrugations selectively engageable with said transverse bar for the extension and retraction of said toe-plate in a step-wise manner.

2. A device in accordance with claim 1, wherein the ends of said sleeves adjacent the linear edge of said toe-plate are crimped against the body of said toe-plate to prevent inadvertent separation of said toe-plate from said frame.

BERNARD CORWIN.
